UNITED STATES PATENT OFFICE

156,650

BRACELET OR SIMILAR ARTICLE

Woodrow W. Pearce and Joseph L. Lockhart,
Los Angeles, Calif.

Application January 10, 1948, Serial No. 143,646

Term of patent 3½ years

(Cl. D45—4)

To all whom it may concern:

Be it known that we, Woodrow W. Pearce and Joseph L. Lockhart, citizens of the United States and residents of Los Angeles, in the county of Los Angeles and State of California, have invented a new, original, and ornamental Design for a Bracelet or Similar Article, of which the following is a specification, reference being had to the accompanying drawing, forming a part thereof.

In the drawing:

Fig. 1 is a perspective view of a bracelet embodying our novel design.

Fig. 2 is a side view of the same, and

Fig. 3 is a plan view.

We claim:

The ornamental design for a bracelet or similar article, substantially as shown.

WOODROW W. PEARCE.
JOSEPH L. LOCKHART.
